WRITING PEN

George S. Walter, Chicago, Ill.

Application April 25, 1936, Serial No. 76,400

10 Claims. (Cl. 120—44)

This invention relates to pens, and particularly to a type of pen, in the use of which, considerable pressure is frequently exerted on the writing end thereof, as, for example, in the use of stylographic pens which are used and are especially well adapted for making carbon copies of original writings.

One object of the present invention is to provide a construction and arrangement whereby portions of the pen are protected against scooping up dust, dirt, paper fibers and the like, which tend to clog the ink passage and seriously interfere with the efficient operation of the pen.

Another object of the invention is to provide a stiff-non-spreading writing portion capable of receiving pressures suitable for producing carbon copies.

Another object of the invention is to provide a pen of the character described with a self-contained mechanical filler, or, in other words, a pen of the stylographic type which is capable of being filled without resorting to the old method of using a dropper or the like, which is still employed in filling pens of the stylographic type.

Another object of the invention is to provide a writing pen having a novel form of vent for admitting air to the reservoir to replace the ink as it is removed therefrom in the operation of the pen, and to provide for convenient filling of the reservoir.

A further object of the invention is to provide a construction and arrangement, wherein a core member is mounted in relatively fixed position in the nozzle or writing portion of the pen, and wherein the discharge opening for the ink is positively determined and remotely positioned with respect to the writing or contact portion of the pen point.

A still further object of the invention is to improve devices of the character described in sundry details hereinafter referred to and more particularly pointed out in the appended claims.

One embodiment of the present invention is shown for illustrative purposes in the accompanying drawing, in which:

Fig. 1 is an elevational view of a pen embodying features of the present invention;

Fig. 2 is an enlarged longitudinal sectional elevational view taken substantially as indicated by the line 2—2 of Fig. 1, the central portion of Fig. 2 being broken away to permit of showing the structure on a considerably enlarged scale;

Fig. 3 is a further enlarged fragmentary elevational view of the structure adjacent the lower end portion of Figs. 1 and 2;

Fig. 4 is a transverse sectional view taken as indicated by the line 4—4 of Fig. 2;

Fig. 5 is an enlarged plan sectional view taken as indicated by the line 5—5 of Fig. 2; and

Fig. 6 is an enlarged plan sectional view taken as indicated by the line 6—6 of Fig. 2.

The illustrative embodiment of the invention comprises a body portion, indicated as a whole by the numeral 11, and shown, in the present instance, as comprising a hollow tubular barrel 12 having a bulb 13 formed of rubber or other suitable flexible and resilient material positioned in one end of the barrel 12, and a nozzle, indicated as a whole by the numeral 14, positioned in the opposite end thereof, the said nozzle being shown, in the present instance, as comprising a tapered portion 15 having a tubular shell or sleeve 16 positioned therein and extending beyond the outer end thereof, the said nozzle 14 and, if desired, the barrel 12 providing a container or reservoir 17 for maintaining a supply of ink within the device for writing purposes.

Removably mounted within the sleeve 16 and extending, preferably, into the interior of the body portion 11 is a core member, indicated as a whole by the numeral 18, and provided with an annular flange 19 adjacent its lower end adapted, preferably, to engage the inner face of the sleeve 16, preferably, adjacent the lower end thereof in a manner to position the core member 18 therein and in spaced relation with respect thereto in a manner to form an annular ink channel 21 communicating adjacent its upper end with the lower end of the reservoir 17, the flange 19 serving also to close the extreme lower end of the ink channel 21.

For securing the core member 18 in proper alignment with the body portion 11 of the pen and in relatively fixed position with respect thereto, a ring 22 may be positioned in a recess 23 formed in the upper end portion of the nozzle 14 and secured therein by an adjacent portion of the tubular barrel 12 when the nozzle and barrel are assembled in the manner illustrated in Fig. 2, the ring 22 being provided with a plurality of 45 inwardly extending inclined spring fingers 24, shown, in the present instance, as three in number, adapted to yieldingly engage the core 18, and provided with upwardly extending end portions 25 adapted to facilitate the positioning of the core 50 between the respective fingers, the core 18, in the present instance, being shown as provided adjacent the fingers 24 with a pair of longitudinally spaced lugs or annular ribs 26 adapted to engage the fingers 24 at the upper and lower portions 55

thereof in a manner to maintain the core member 18 against longitudinal displacement with respect to the body portion 11 and nozzle 14.

For obtaining ink from the reservoir 17 and ink channel 21 for writing purposes, the tubular shell or sleeve 16 is provided adjacent its lower end portion with a plurality of annularly spaced discharge openings 27 formed therein and communicating with the ink channel 21 adjacent the lower end thereof, the openings or apertures 27 being shown, in the present instance, as longitudinally extending elongated substantially parallel slots uniformly spaced around the tubular shell or sleeve 16 in a manner to discharge the ink laterally or in a radial direction from the ink channel 21, and for assisting in directing the ink toward the writing side of the pen, the portions of the shell or sleeve 16 between the respective slots 27 are grooved adjacent their lower edge portions as indicated at 28, the extreme lower edge 29 of the sleeve 16 being slightly rounded in the manner shown to provide a smooth edge portion for contact with the writing surface on which the pen is used.

It will be noted that the core member 18 is shown, in the present instance, as provided with an air vent 31 formed therein and extending therethrough to permit of the admission of air into the interior of the body 11 and reservoir 17 to replace the ink used in the writing operation of the pen, and providing also an intake passage through which ink may be drawn into the pen during the filling operation by manipulation of the bulb 13, the ink during the filling operation being discharged from the upper or inner end of the opening 31 into the reservoir 17.

Mounted on the upper or inner end portion of the tubular core member 18 is an outwardly extending annular flange 32 adapted to restrict the opening in the barrel 12 surrounding the flange 32 and to direct or concentrate the air expelled from the bulb 13 toward or at the upper end of the opening 31 of the tubular core 18 during the filling operation.

It will be understood that in the filling operation, the bulb 13 may be compressed and the lower end of the nozzle 14 placed in a bottle or other supply of ink, in which condition, upon releasing the bulb, the resiliency thereof will cause the bulb to expand to its normal form and in so doing will draw ink through the opening 31 of the tubular core 18, from which it will overflow at the upper end thereof into the reservoir 17. If it is desired to draw more ink into the reservoir thereafter, the bulb 13 may again be compressed, and the air expelled therefrom will be concentrated and discharged through the opening 31 of the core 18 due to the restriction of the opening in the barrel 12 by reason of the flange 32 positioned therein, thus preventing the expelled air from forcing the ink in the reservoir outwardly through the channel 21 and apertures 27. Thereafter, the bulb 13 may again be released and a second charge of ink drawn into the pen through the opening 31 of the core member 18 to be discharged from the upper end thereof into the reservoir 17.

For protecting the bulb 13 against accidental compression during the handling of the pen or when the pen is in use, a cap or cover 33 may be screw-threaded or otherwise secured to the upper end of the barrel 12.

It will be observed from the foregoing description that the present invention provides a novel construction and arrangement for directing the

ink from the ink channel to the writing point of the pen, and for maintaining the tubular core member in substantial alignment and against accidental displacement with respect to the body portion and nozzle, also that the present invention provides novel means for facilitating the filling of the pen.

Obviously, the present invention is not limited to the precise construction and arrangement shown and described as the same may be variously modified. Moreover, all the features of the invention need not be used conjointly as the same may be used to advantage in variously different combinations and subcombinations.

What I claim as new and desire to secure by Letters Patent is:

1. In a fountain pen having a body portion and a hollow nozzle mounted thereon providing an ink reservoir, the combination of a core member positioned in and extending through the opening formed in said nozzle in spaced relation thereto to provide an ink channel communicating with said reservoir, the lower end portion of said member engaging the lower end portion of said nozzle for completely closing the lower end of said channel, said nozzle having a plurality of annularly spaced discharge openings formed therein and communicating with said ink channel for discharging the ink laterally therefrom.

2. In a fountain pen having a body portion and a hollow nozzle mounted thereon providing an ink reservoir, the combination of a core member positioned in and extending through the opening in said nozzle in spaced relation thereto to provide an ink channel communicating at its upper end with said reservoir, the lower end portion of said member having an annular flange engaging the adjacent lower end portion of said nozzle for completely closing the lower end of said channel, said nozzle having a plurality of spaced elongated substantially parallel discharge slots formed therein communicating with said ink channel for discharging the ink laterally therefrom.

3. In a fountain pen having a body portion and a hollow nozzle mounted thereon providing an ink reservoir, the combination of a core member positioned in and extending through the opening in said nozzle in spaced relation thereto to provide an ink channel communicating at its upper end with said reservoir, the lower end portion of said member having an annular flange engaging the adjacent lower end portion of said nozzle for completely closing the lower end of said channel, said nozzle having a plurality of elongated substantially uniformly spaced discharge slots formed therein communicating with said ink channel for discharging the ink laterally therefrom.

4. In a fountain pen having a body portion and a hollow nozzle mounted thereon providing an ink reservoir, the combination of a core member positioned in and extending through the opening in said nozzle in spaced relation thereto to provide an ink channel communicating at its upper end with said reservoir, the lower end portion of said member having an annular flange engaging the adjacent lower end portion of said nozzle for completely closing the lower end of said channel, said nozzle having a plurality of elongated annularly spaced discharge slots formed therein communicating with said ink channel for discharging the ink laterally therefrom and having annularly extending grooves

formed in the portions of the nozzle between said slots.

5. In a fountain pen having a body portion and an elongated hollow nozzle mounted thereon providing an ink reservoir, the combination of a core member positioned in and extending through the opening in said nozzle in spaced relation thereto to provide an annular ink channel communicating at its upper end with said reservoir, the lower end portion of said member having an annular flange engaging the adjacent lower end portion of said nozzle for completely closing the lower end of said channel, said nozzle having a plurality of elongated annularly spaced longitudinally disposed discharge slots formed therein communicating with said ink channel for discharging the ink laterally therefrom and having annularly extending grooves formed in the portions of the nozzle between said slots.

20. 6. In a fountain pen having a body portion and an elongated hollow nozzle mounted thereon providing an ink reservoir, the combination of a core member positioned in and extending through the opening in said nozzle in spaced relation thereto to provide an annular ink channel communicating at its upper end with said reservoir, the lower end portion of said member having an annular flange engaging the adjacent lower end portion of said nozzle for completely closing the lower end of said channel, said nozzle having a plurality of elongated annularly spaced longitudinally disposed discharge slots formed therein communicating with said ink channel for discharging the ink laterally therefrom and having a plurality of annularly extending grooves formed in the respective portions of the nozzle between said slots, said grooves being spaced inwardly from the adjacent end of said nozzle.

7. In a fountain pen having a hollow body portion and a hollow nozzle mounted thereon providing an ink reservoir, the combination of a tubular core member positioned in said body portion and communicating with the interior thereof, said core member extending through the opening formed in said nozzle in spaced relation thereto to provide an ink channel communicating with said reservoir, the lower end portion of said member engaging the lower end portion of said nozzle for completely closing the lower end of the channel, said nozzle having a plurality of annularly spaced discharge openings formed therein and communicating with said ink channel for discharging the ink laterally therefrom, and supporting means mounted in said body portion adjacent the connection thereof with said nozzle and engaging said tubular core member for maintaining the core member in relatively fixed position longitudinally and in substantial alignment with respect to said body portion and nozzle.

8. In a fountain pen having a hollow body portion and a hollow nozzle mounted thereon providing an ink reservoir, the combination of a tubular core member positioned in said body portion and communicating adjacent its upper end with the interior thereof, said core member extending through the opening in said nozzle in spaced relation thereto to provide an ink channel communicating at its upper end with said reservoir, the lower end portion of said member having an annular flange in alignment with said channel and engaging the adjacent lower end portion of said nozzle for completely closing the

lower end of the channel, said nozzle having a plurality of spaced elongated substantially parallel discharge slots formed therein communicating with said ink channel for discharging the ink laterally therefrom, and resilient supporting means secured between said body portion and nozzle and engaging said tubular core member substantially midway between its ends for maintaining the core member in relatively fixed position and in substantial alignment with respect to said body portion and nozzle.

9. In a fountain pen having a hollow body portion and a hollow nozzle mounted thereon providing an ink reservoir, the combination of a tubular core member positioned in said body portion and communicating adjacent its upper end with the interior thereof, said core member extending through the opening in said nozzle in spaced relation thereto to provide an ink channel communicating at its upper end with said reservoir, a laterally extending flange adjacent the upper end of said tubular core, the lower end portion of said core member having an annular flange in alignment with said channel and engaging the inner surface of the adjacent lower end portion of said nozzle for completely closing the lower end of the channel, said nozzle having a plurality of spaced elongated substantially parallel discharge slots formed therein communicating with said ink channel for discharging the ink laterally therefrom, resilient supporting fingers mounted in said body portion adjacent the connection thereof with said nozzle and engaging said tubular core member for maintaining the core member in relatively fixed position and in substantial alignment with respect to said body portion and nozzle, and means on said core member engaging said fingers for normally maintaining the member against longitudinal displacement with respect to said body portion and nozzle.

10. In a fountain pen having a hollow body portion and a hollow nozzle mounted thereon providing an ink reservoir, the combination of a tubular core member positioned in said body portion and communicating adjacent its upper end with the interior thereof, said core member extending through the opening in said nozzle in spaced relation thereto to provide an ink channel communicating at its upper end with said reservoir, a laterally extending annular flange adjacent the upper end of said tubular core, the lower end portion of said core member having an annular flange in alignment with said channel and engaging the adjacent lower end portion of said nozzle for closing the lower end of the channel, said nozzle having a plurality of spaced elongated substantially parallel discharge slots formed therein communicating with said ink channel for discharging the ink laterally therefrom, a ring mounted between the adjacent ends of said body portion and nozzle, inwardly extending resilient fingers mounted on said ring and engaging said tubular core member for maintaining the core member in relatively fixed position and in substantial alignment with respect to said body portion and nozzle, and longitudinally spaced lugs on said core member engaging said fingers for removably maintaining the said core member against longitudinal displacement with respect to said body portion and nozzle.
